Tyne, England, a company of Great Britain

Application September 29, 1942, Serial No. 460,161
In Great Britain September 25, 1941

7 Claims. (Cl. 200—148)

This invention relates to an electric circuit-breaker of the kind in which a blast of de-ionising gas is caused to flow through a nozzle to assist in extinguishing the arc. In such circuit-breakers the arc is usually drawn out by relative movement of the arcing contacts, but for efficient operation it is desirable for the nozzle to be of relatively small size, and this gives rise to difficulty in cases where the normal current-carrying capacity required involves comparatively large contact surfaces.

The present invention has for its object to avoid this difficulty and at the same time to afford increased speed and certainty of operation.

The circuit-breaker according to the invention comprises a pair of fixed arcing contacts one of which is constituted by or is situated at and connected to the low pressure end of the nozzle itself whilst the other is supported from the high pressure side of the nozzle, and a movable bridging contact member which normally bridges the gap between the fixed arcing contacts or members electrically connected thereto and by whose movement the arc is initially formed on the high pressure side of the nozzle, the arc being blown by the gas-blast so that one arc root moves along the nozzle from the high pressure end to the low pressure end thereof and the arc is caused to take up a position favourable to arc extinction extending between the arcing contacts.

The fixed arcing contact supported from the high pressure side of the nozzle is conveniently constituted by the end of a rod or tube disposed substantially in alignment with the nozzle axis, and in this case the fixed arc-initiating contact, with which the bridging contact member cooperates may be constituted by the arcing contact rod or tube or by a tube surrounding it and electrically connected to it. Alternatively the bridging contact member itself may be constituted by a tube surrounding and electrically connected to the arcing contact rod or tube. The bridging contact member preferably moves in a direction substantially parallel to the nozzle axis.

Two convenient practical constructions according to the invention are illustrated by way of example in longitudinal section respectively in the two figures of the accompanying drawing.

In the arrangement of Figure 1, the circuit-breaker is enclosed within a casing A of generally cylindrical form, to one end of which gas under pressure is introduced, when required, from a suitable reservoir, whilst the other end

serves for the discharge of the gases. At a suitable position in the length of the casing A a metal nozzle B diverging towards the discharge end is mounted in a metal housing B¹ secured 5 in the casing A, and the inner surface B² of such housing is formed as a cylinder in which can slide a piston C¹ carrying a bridging contact member C in the form of a group of inwardly spring-pressed contacts. This piston C¹ is moved 10 by the gas pressure in a direction towards the discharge end of the casing against the action of a spring C², and the nozzle B is provided with an external contact surface B³ with which the bridging contact member C always remains in 15 engagement throughout the piston stroke.

In the normal closed position of the circuit-breaker the bridging contact member C serves to bridge the gap between the nozzle B and a fixed tube D mounted on the high pressure side of 20 the nozzle in axial alignment therewith. This tube D surrounds and is connected by webs D¹ to a central rod D², whose end D³ nearest the nozzle B constitutes one of the arcing contacts of the circuit-breaker. The other arcing contact is constituted by the low pressure end of 25 the nozzle B itself, the two arcing contacts thus both being fixed at an appropriate distance apart, the gap between them or between members electrically connected thereto normally being closed 30 by the bridging contact member C.

When it is desired to open the circuit-breaker, gas under pressure is admitted to the casing A and acts on the piston C¹ to drive it towards the discharge end of the casing within the metal housing B¹, thus breaking the connection between the tube D and the bridging contact member and drawing out an arc between them. The gas-blast acts on this arc immediately it is formed and tends to blow it through the nozzle B. 35 One arc root remains anchored on the arcing contact constituted by the end D³ of the rod D², whilst the other arc root is blown across from the bridging contact member C on to the high pressure end of the nozzle B and thence along 40 the nozzle surface to the second arcing contact at the low pressure end. In this position the arc will be to some extent bowed out through the nozzle and its main length, at least, will lie more or less along the axis of the nozzle in a 45 position favourable to arc extinction by the gas-blast.

The arrangement of Figure 2 shows a modified arrangement of the arcing contacts. The casing A, the nozzle B and metal housing B¹ and the 50 bridging contact member C and its piston C¹ and

spring C² are arranged as in Figure 1. The tube D and rod D² are however replaced in this modification by a simple rod F, with which the bridging contact member C normally engages. The arc is initially formed between the contact member C and the rod F, and is at once blown through the nozzle by the gas-blast and is transferred thereby to the two arcing contacts, one of which is constituted by a tip F¹ on the end of the rod F. The other arcing contact may again be constituted by the low pressure end of the nozzle B, or (as shown) by a separate contact B⁴ centrally mounted at the low pressure end of the nozzle and connected thereto by webs B⁵.

The gap between the fixed arcing contacts is chosen to suit the conditions of the circuit on which the circuit-breaker is to be installed, and for voltages below say 11,000 volts, it is convenient to extend the arcing tip F¹, as shown in Figure 2, to a position fairly close to the second arcing contact.

The operation of this arrangement will be at once clear from the description above given of that for the arrangement of Figure 1, and it will be realised that the tube D and rod D² of Figure 1 or the simple rod F of Figure 2 may be replaced by a simple tube D without the central rod (the front edge of the tube then acting as arcing contact). The use of the open tube D, with or without the central rod, has the advantage that gas can flow through the tube as well as outside it, thus improving the action of the gas-blast on the arc in the nozzle.

The use of an open tube, with its edge acting as arcing contact has the further advantage of enabling the invention to be combined with that of the concurrent United States of America patent application Serial No. 460,160 in the names of the present applicants. In such case a central rod similar to the rod D³ is provided but is insulated from the tube D and connected thereto through a resistance, which comes into action when the arc is established between the end of such central rod and the low pressure end of the nozzle (or the separate contact B⁴ if employed) so that the arc current is then limited by the series resistance and is readily and easily extinguished by the gas-blast.

It will be appreciated that the foregoing constructions have been described by way of example only and that the invention can be carried into practice in other ways.

What we claim as our invention and desire to secure by Letters Patent is:

1. An electric circuit-breaker, including in combination a nozzle of conducting material, means whereby a blast of deionising gas is caused to flow through the nozzle, a pair of fixed arcing contacts, one of which is situated at the low pressure end the nozzle, means for supporting the other fixed arcing contact from the high pressure side of the nozzle, a fixed arc initiating contact electrically connected to such other arcing contact, a movable arc initiating contact permanently connected electrically to the nozzle and normally engaging with the fixed arc initiating contact and thereby bridging the electrical gap between the two arcing contacts, spring means for urging the movable contact towards its normal position, and a piston carried by the movable contact and exposed to the pressure of the gas-blast

against the spring action whereby such gas pressure causes the movable contact to move remaining connected to the nozzle but breaking contact with the fixed arc initiating contact and thereby drawing out the arc on the high pressure side, the arc being blown by the gas-blast so that one arc root moves along the nozzle from the high pressure end to the low pressure end thereof and the arc is caused to take up a position favorable to arc extinction extending between the two fixed arcing contacts.

2. An electric circuit-breaker as claimed in claim 1, in which the fixed arcing contact at the low pressure end of the nozzle is constituted by part of the nozzle itself.

3. An electric circuit-breaker as claimed in claim 1, in which the arcing contact supported from the high pressure side of the nozzle is constituted by the end of a rod-like member disposed substantially in alignment with the nozzle axis.

4. An electric circuit-breaker as claimed in claim 1, in which the fixed arcing contact supported from the high pressure side is constituted by the end of a rod disposed substantially in alignment with the nozzle axis, and the fixed arc-initiating contact is constituted by part of a tube surrounding such rod and electrically connected thereto.

5. An electric circuit-breaker as claimed in claim 1, including means mounting the movable contact for displacement substantially parallel to the nozzle axis and generally in the direction of the gas flow through the nozzle.

6. An electric circuit-breaker, including in combination a nozzle of conducting material, means whereby a blast of deionising gas is caused to flow through the nozzle, a pair of fixed arcing contacts, one of which is situated at the low pressure end of the nozzle, is disposed generally centrally in the gas stream flowing through the nozzle and is electrically connected to the nozzle, means for supporting the other fixed arcing contact from the high pressure side of the nozzle, a fixed arc-initiating contact electrically connected to such other arcing contact, a movable arc-initiating contact permanently connected to the nozzle and normally engaging with the fixed arc-initiating contact and thereby bridging the electrical gap between the two arcing contacts, spring means for urging the movable contact towards its normal position, and a piston carried by the movable contact and exposed to the pressure of the gas-blast against the spring action whereby such

gas pressure causes the movable contact to move while remaining connected to the nozzle but breaking contact with the fixed arc-initiating contact and thereby drawing out the arc on the high pressure side, the arc being blown by the gas-blast so that one arc root moves along the nozzle from the high pressure end to the low pressure end thereof and the arc is caused to take up a position favorable to arc extinction extending between the two fixed arcing contacts.

7. An electric circuit-breaker as claimed in claim 1 in which the movement of the movable contact takes place substantially parallel to the axis of the nozzle generally in the direction of the gas flow through the nozzle.

DONALD FOSTER AMER.
WALTER HENRY WEBB.
